BELLOWS TRIMMING MACHINE

Samuel W. Steele, Knoxville, Tenn., assignor to
 Robertshaw-Fulton Controls Company, Knoxville, Tenn., a corporation of Delaware

Application October 1, 1947, Serial No. 777,304

8 Claims. (Cl. 164—38)

1

This invention relates to a machine for trimming the ends of tubular elements, and more particularly the ends from expansible and collapsible corrugated tubular walls, commonly called bellows.

One-piece bellows are usually made by blanking a disk from sheet metal, drawing the disk into a tube of smaller or greater length depending upon the number of corrugations to be formed in the cylindrical wall, and then deeply corrugating the tubular wall, as for example by hydrostatic pressure. The completed bellows as so produced has its open end of greater or less extension beyond the nearest adjacent corrugation, and also of more or less irregularity, so that it is customary to trim off the extreme end of the so corrugated tube to the end that the finished product will have a predetermined overall length, within manufacturing tolerances, and also a regular extremity.

It is an object of this invention to provide a bellows trimming machine of improved construction by which the bellows may be economically trimmed at relatively high speed.

Another object of this invention is to provide an improved machine of the type characterized which assures uniformity in the extent to which the trimmed bellows project beyond the nearest corrugation.

Another object of this invention is to provide an improved machine of the type characterized which involves a minimum of intervention by the operator so as to eliminate as nearly as may be the variations due to human error, and thereby enable the machine to be run by relatively unskilled workmen.

Another object of this invention is to provide an improved machine of the type characterized with a safety device which will minimize chances of injury to the operator.

Another object of this invention is to provide an improved machine of the type characterized with pneumatic provisions for removing the trimmed bellows and trimmings.

Another object of this invention is to provide an improved machine of the type characterized which is simple in construction, economical to operate, and highly efficient in the high speed trimming of bellows.

Other objects will appear as the description of the invention proceeds.

The invention is capable of receiving a variety of mechanical expressions only one of which has been illustrated on the accompanying drawings, and it is therefore to be expressly understood that

2

the drawings are for purposes of illustration only, and are not to be construed as definitions of the limits of the invention, reference being had to the appended claims for that purpose.

5 Referring in detail to the accompanying drawings, wherein the same reference characters are used to designate corresponding parts in the several figures,

10 Fig. 1 is a somewhat diagrammatic plan view of a machine embodying the present invention;

Fig. 2 is a corresponding side elevation with certain parts broken away to illustrate others;

Fig. 3 is a cross section on the line 3—3 of Fig. 1; and

15 Fig. 4 is an enlarged detail.

In the form shown the frame of the machine includes a platform 10 having an aperture 11 in which is secured a tubular block 12 flanged at its upper end at 13 where it is secured to the

20 platform 10 by any suitable number of bolts or screws 14. Mounted in said block 12 in any suitable way as by threading is an exteriorly threaded bearing sleeve 15 having an interiorly threaded collar 16 locked thereto against rotation by

25 set screw 17. Received in said bearing sleeve 15 is a stub shaft 18 secured against upward movement by a collar 19 locked to the shaft by set screw 20. The lower end of shaft 18 is reduced in diameter and mounted thereon is a pulley 21

30 suitably secured to the shaft as by a set screw 22. Pulley 21 may be driven in any suitable way, as by a belt 23 from a pulley 24 driven from any suitable motor through any suitable gearing, the motor being shown as an electric motor

35 25 supported by a bracket 26 at the underside of the platform 10.

The upper end of shaft 18 is somewhat tapered as shown at 27 and suitably secured thereto for rotation with the shaft 18 is a turntable 28, as

40 by a block 29 attached to the shaft by screw 30. Mounted on said turntable is any suitable number of rotatable spindles, six being shown in Fig. 1. As shown, turntable 28 is provided with suitably spaced apertures 31 and mounted in each of

45 said apertures is a stationary bearing block 32 which is flanged at 33 and by which the block is suitably secured to the turntable as by bolts or screws 34. Each block 32 has an extension 35 projecting upwardly therefrom, and extending through said block and extension is an opening

36 which is eccentrically disposed with respect to said extension as clearly shown in Figs. 3 and 4. Mounted in said opening 36 is a spindle 37 which extends below the lower extremity of the block 55 where it is reduced in cross section at 38. Mount-

ed on said extension 38 is a roller 39 of any suitable construction, preferably having a cylindrical portion of friction material as rubber, said roller being secured on said extension in any suitable way as by a nut 41 with one or more washers 40 (see Fig. 4). Secured to the opposite end of the spindle 37, as by a screw 42, is a disk 43 which may be set in a recess at the top of block extension 35 but because of the eccentric relationship of the spindle 37 with respect to said block extension said disk has an overhanging segment 44 for a purpose to be explained.

Suitably secured to the top of the platform 18 is an upstanding block or frame 46 which at its lower end has an inwardly facing concave arcuate face 47 concentric with the axis of the turntable 28 and so positioned that it is engaged by each of the rollers 39 as the turntable 28 is rotated, said arcuate face 47 being of such extent that each roller by engagement therewith will be caused to rotate sufficiently to cause at least one complete revolution of the element to be trimmed mounted on the associated disk 43. The upper end of said block or frame 46 has attached thereto a stationary knife 48 having an inwardly facing concave arcuate edge 50 (see Fig. 4) which slightly underlies the overhang 44 of each disk 43, the length of said cutting edge 50 being such as to be in contact with the element to be trimmed mounted on said disk 43 at least through one complete revolution of said element. Knife 48 is secured on the block 46 in any suitable way, as by two or more threaded studs 51.

Slidably mounted on the top of the knife 48 is a plate 52 lying in the plane of and having substantially the same thickness as each disk 43, said plate 52 being preferably spring urged toward the disk 43, and having an inner concave arcuate edge which is coextensive with the cutting edge 50. As shown, the plate 52 is suitably notched at its rear edge to form tongues 53 which are slotted to cooperate slidably with pins 54 carried by threaded members 55 adjustably retained by nuts 56 in apertures provided in posts 57 mounted on the platform 18 in any suitable way. Surrounding each member 55 and reacting between the bottom 58 of a notch in plate 52 and an abutment nut 59 carried by the member 55 is a coil spring 60. Thereby the plate 52 is resiliently urged to the right as viewed in Fig. 3 to press the element mounted on each disk 43, while opposite the knife edge 50, firmly against the periphery of said disk.

Mounted on top of said plate 52 is a second plate 63 having its inner periphery 64 properly shaped to engage in the corrugation of a bellows which is nearest to the open end thereof, plate 63 being resiliently clamped to plate 52 by coil springs 64 mounted on the studs 51 and reacting between the plate 63 and nuts 65 adjustably mounted on said studs. Plate 52 is slotted at 61 where the studs 51 pass therethrough, and additional headed studs 66 may pass through slots 67 in the plates 52 and 63 and the knife blade 48 for retaining the parts adjustably in their proper relative positions.

To assure that an operator may not have his hand brought into contact with the knife when the machine is running, a safety device is provided which opens the circuit to the electric motor 25 if the operator thrusts his hand toward the knife when the machine is running. As shown in Figs. 1 and 2, an upstanding post 70 carried by the top of platform 18 has suitably secured thereto, as by nuts 71, a rod 72 on which is pivotally mounted a guard 73 shown as of in-

verted U-shaped configuration to provide a gap 74 through which the spindle blocks 32, 35 with the elements mounted on disks 43 may pass, said guard providing downwardly projecting extensions 75 and 76 which close the space by which access can be gained to the elements being trimmed while in contact with the knife edge 50. Suitably secured on said post 70 is a bracket 77 carrying a housing 78 in which is disposed any suitable spring actuated switch which is normally closed and has an actuating member 79 projecting exteriorly thereof into a position to be engaged and operated by the guard 73 if thrust toward the housing 78. Accordingly when guard 73 is rotated around its pivot 72 by the operator trying to thrust his hand into opening 74 the switch actuator 79 opens the switch against the tension of its spring and stops the motor. Suitable cables extend from the switch 78 to the motor 25, being shown as housed in a pipe or casing 80.

The machine is also preferably constructed so that the removal of a trimmed element from each disk 43, and also the removal of the trimmings are effected pneumatically. As shown more particularly in Fig. 2, a conduit 82 controlled by a suitable valve 83 leads to a T coupling 84 from which extend pipes 85 and 86. Suitable pressure reducing valves 87 may be employed to secure the desired pressures in pipes 85 and 86. Pipes 85 and 86, respectively, extend to nozzles 88 and 89 (shown broken off in Fig. 2), where they are respectively disposed at opposite sides of a station 94 through which each spindle 37 passes soon after leaving the knife 48 and its associated plates 52 and 63. Nozzle 88 is so located with respect to an element mounted on a disk 43 that said element is blown therefrom into a downwardly inclined tubular chute 90 leading to a tray or other suitable receptacle 91. Nozzle 89 is so disposed that the trimming which has dropped downwardly onto the flange 33 around the extension 35 is blown upwardly and into a downwardly inclined tubular chute 92 leading to a tray or other suitable receptacle 93.

In operation, a bellows to be trimmed is mounted on each disk 43, with its open end facing downwardly as shown in Fig. 4, when each disk 43 reaches the station generally designated 95. The bellows is then supported on said disk 43 by the lower wall of the first inwardly extending corrugation 102 resting on the disk 43, the extent of contact of the disk 43 with said corrugation being sufficient to support the bellows in position. Assuming that the turntable 28 is being constantly rotated at the proper rate because of the relative sizes of the pulleys 21 and 24 and any reduction gearing incorporated in the motor 25, rotation of the turntable 28 in the direction of the arrow 86 in Fig. 1 will bring the bellows supported on the disks 43 in succession into cooperative relationship with the knife 48 and the spring pressed plates 52 and 63, the rollers 39 simultaneously being brought into cooperative relationship with the arcuate surface 47. Plates 52 and 63 will engage the tubular extension at the open end of the bellows in the plane of the disk 43, and the corrugation immediately adjacent thereto, so as to hold the bellows firmly on and against the disk 43. Roller 39 being so constructed and arranged that a driving engagement is set up between the same and the arcuate surface 47, each spindle 37 is rotated by its roller 39 rolling on the arcuate surface 47, and therefore its associated disk 43 is rotated, causing the bellows thereon to roll on the arcuate edges of the plates 52 and 63, while

the cutting edge 50 has cutting engagement with the periphery of the tubular wall surrounding the open end of the bellows. As the duration of contact between the roller 39 and the arcuate surface 47 is sufficient to cause a complete revolution of the bellows mounted on each disk 43, the open end portion of the bellows is trimmed off at a predetermined distance from the adjacent wall of the nearest corrugation. At the completion of a revolution of the bellows, the roller 39 passes out of driving contact with the arcuate surface 47 and the spindle 27 ceases to rotate.

When the spindle reaches the station generally indicated 94 in Fig. 1, the nozzle 88 first blows the trimmed bellows off the disk 43 whereupon it is received in the inclined chute 90 and falls into the tray 91. Thereafter, the nozzle 89 blows the trimming which has fallen onto the flange 33 into the inclined chute 92 whereupon it is delivered to tray 93.

The vertical relationship between the disk 43 and the edge of the trimming knife 48 may be adjusted by threading the bearing sleeve 15 into or out of the block 12, to raise or lower the turntable 28, and then locking the parts in adjusted position by the collars and set screws above described.

It will therefore be perceived that the present invention provides a simple machine that can be operated by relatively unskilled labor and at relatively high speed to trim off the open ends of bellows to a predetermined distance from the corrugation nearest the open end, thereby largely if not entirely eliminating the variations incident to trimming under manual control. Once the machine is set the operator merely has to place the bellows in position, following which all subsequent operations are automatic, the trimmed bellows being delivered from the machine in rapid succession. By reason of the safety provision, danger that the operator will have his fingers drawn into contact with the trimming knife has been obviated, and by reason of the pneumatic provisions the trimmings as well as the trimmed bellows are automatically removed from the machine. The machine is highly efficient in operation and can be readily driven at a speed such that the rate of trimming bellows may be materially increased over that heretofore obtained.

While the embodiment of the invention illustrated on the drawings has been described with considerable particularity, it is to be expressly understood that the invention is not limited thereto, as the same is capable of receiving a variety of mechanical expressions, as will now be apparent to those skilled in the art, while changes may be made in the details of construction, sizes, arrangements, proportion of parts, etc., and parts may be replaced by equivalent parts, without departing from the spirit of this invention. While the invention has been described with respect to its application to the trimming of bellows for which it has particular utility, it will also be apparent that it may also be used to advantage for the trimming of other tubular elements. Reference is therefore to be had to the appended claims for a definition of said invention.

What is claimed is:

1. In an apparatus of the character described, the combination of a rotatable turntable, a plurality of bearing blocks mounted on said turntable, a spindle rotatably mounted in each of said blocks and offset with respect to the axis thereof and projecting beyond the same, a driv-

ing roller on the projecting end of each spindle, disk means for supporting an element to be trimmed on each spindle and partially extending beyond its respective bearing block, means providing a concave arcuate surface concentric with the axis of said turntable and positioned to be engaged by each driving roller to rotate the same as the turntable rotates each spindle past said surface, and a stationary arcuately concave trimming member concentric with the axis of said turntable and engageable with the element on each supporting means while said element and supporting means is being rotated by the associated spindle.

2. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, disk means for supporting an element to be trimmed on each spindle and partially extending beyond its respective bearing block, a member providing a concave arcuate surface concentric with the axis of said turntable and positioned to be engaged by each driving roller to rotate the same for at least a complete revolution of an element on said supporting means, a stationary arcuately concave trimming member concentric with the axis of said turntable and carried by said first member, said trimming member being engageable with the element on each supporting means for at least a complete revolution of said element while said element and supporting means is being rotated by the associated spindle.

3. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, means for supporting an element to be trimmed on each spindle, means providing a concave arcuate surface concentric with the axis of said turntable and positioned to be engaged by each driving roller to rotate the same as said turntable rotates each spindle past said surface, a stationary arcuately concave trimming member concentric with the axis of said turntable and engageable with the element on each supporting means while said element and supporting means is being rotated by the associated spindle, and means resiliently mounted on said trimming member for pressing each element against its supporting means while the element is in engagement with said trimming member.

4. In an apparatus of the character described, the combination of a rotatable turntable, a plurality of bearing blocks mounted on said turntable, a spindle rotatably mounted in each of said blocks and projecting beyond the same, a driving roller at the projecting end of each spindle, means for supporting an element to be trimmed on each spindle, a member providing a concave arcuate surface concentric with the axis of said turntable and positioned to be engaged by each driving roller to rotate the same as said turntable rotates each spindle past said surface, a stationary arcuately concave trimming member concentric with the axis of said turntable and engageable with the element on each supporting means while said element and supporting means is being rotated by the associated spindle, and means associated with said trimming member for pressing each element against its supporting

means while the element is in engagement with said trimming member, said last named means including a stationary arcuately concave member concentric with the axis of said turntable and with which the element has rolling contact while in engagement with said trimming member.

5. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, means for supporting an element to be trimmed on each spindle, a member providing a concave arcuate surface concentric with the axis of said turntable and positioned to be engaged by each driving roller to rotate the same as said turntable rotates each spindle past said surface, a stationary arcuately concave trimming member concentric with the axis of said turntable and engageable with the element on each supporting means while said element and supporting means is being rotated by the associated spindle, and means associated with said trimming member for pressing each element against its supporting means, said last named means including a stationary member mounted on said trimming member and having an arcuate concave surface coextensive and concentric with the edge of said trimming member for holding the element being trimmed firmly against said supporting means.

6. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, means for supporting an element to be trimmed on each spindle, means providing a concave arcuate surface concentric with the axis of said turntable and positioned to be engaged by each driving roller to rotate the same as said turntable rotates each spindle past said surface, a stationary arcuately concave knife concentric with the axis of said turntable and engageable with the element on each supporting means while said element and supporting means is being rotated by the associated spindle, and means associated with said trimming member for pressing each element against its supporting means, said last named means including a stationary member having an arcuate concave surface coextensive and concentric with the edge of said trimming member for holding the element being trimmed firmly against said supporting means and resil-

ient means cooperating with said last named member for pressing the same into contact with the element on each supporting means.

7. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, means for supporting an element to be trimmed on each spindle, means providing a concave arcuate surface concentric with the axis of said turntable and positioned to be engaged by each driving roller to rotate the same as the turntable rotates each spindle past said surface, a stationary arcuately concave trimming member concentric with the axis of said turntable and engageable with the element on each supporting means while said element and supporting means is being rotated by the associated spindle, and pneumatic means associated with said turntable for severally removing the trimmed element and the trimming after the element is rotated by said turntable past said trimming member.

8. In an apparatus of the character described, the combination of a rotatable turntable, a plurality of bearing blocks mounted on said turntable, a spindle rotatably mounted in each of said blocks and projecting beyond the same, a driving roller on the projecting end of each spindle, means for supporting an element to be trimmed on each spindle, means providing a concave arcuate surface concentric with the axis of said turntable and positioned to be engaged by each driving roller to rotate the same as said turntable rotates each spindle past said surface, a stationary arcuately concave trimming member concentric with the axis of said turntable and engageable with the element on each supporting means while said element and supporting means is being rotated by the associated spindle, means for rotating said turntable, an electric switch in circuit with said motor, and guard means operable to close said switch only when in position to shield said trimming member.
